UNITED STATES PATENT OFFICE.

WILLIAM WHARTON, JR., AND EDWARD SAMUEL, OF PHILADELPHIA, PENNSYLVANIA, ASSIGNORS TO WILLIAM WHARTON, JR., & CO., (LIMITED,) OF SAME PLACE.

DESIGN FOR A RAILWAY-RAIL.

SPECIFICATION forming part of Design No. 17,191, dated March 15, 1887.

Application filed January 7, 1887. Serial No. 225,705. Term of patent 14 years.

To all whom it may concern:

Be it known that we, WILLIAM WHARTON, Jr., and EDWARD SAMUEL, citizens of the United States, residing in Philadelphia, Pennsylvania, have invented a new and original Design for a Railway-Rail, of which the following is a specification.

Our design for a railway-rail is fully illustrated in the accompanying drawing, the view 10 in which is a transverse section showing the outline of the rail.

The rail has a head portion, *a*, with depending web *b* and two lateral flanges, *d d*, each flange having on its upper side a depression, 15 *c*, and the under side of the rail is hollowed out at *f* on each side of the web *b*, and curves *g* extend from the hollowed-out portions *f f*.

We claim—

The herein-described design for a railway-rail having in transverse section the outline illustrated, comprising the head *a*, web *b*, and flanges *d d*, with their tops depressed, the under side of the rail being hollowed out at *f* on each side of the web, substantially as shown and described. 20

In testimony whereof we have signed our names to this specification in the presence of two subscribing witnesses.

WILLIAM WHARTON, JR.
EDWD. SAMUEL.
